UNITED STATES PATENT OFFICE.

JUNIUS A. BOWDEN, OF LOS ANGELES, CALIFORNIA.

DESIGN FOR A DIVERTING-REFLECTOR FOR HEADLIGHTS.

48,853.

Specification for Design.

Patented Apr. 11, 1916.

Application filed January 15, 1916. Serial No. 72,356. Term of patent 7 years.

To all whom it may concern:

Be it known that I, JUNIUS A. BOWDEN, a citizen of the United States, residing at Los Angeles, in the county of Los Angeles and State of California, have invented a new, original, and ornamental Design for Diverting - Reflectors for Headlights, of which the following is a specification, reference being had to the accompanying drawing, forming part hereof.

In the drawing, Figure 1 is a front ele-

vation of a diverting reflector for headlights, showing my new design, and Fig. 2 is a side elevation thereof.

I claim:

The ornamental design for a diverting reflector for headlights, as shown.

In testimony whereof I have hereunto set my hand, at Los Angeles, California, this 8th day of January, 1916.

JUNIUS A. BOWDEN.
